and of certain structural details, and to secure the same in the form and in the arrangement shown, to the end of enabling the same to be used as a reel for clothes lines, and for other purposes, as will be more fully described hereinafter, and for which purpose there is provided a device, the principal parts of which are shown in the drawings, and which is described in the following specification, which may be read together with the claims, to fully understand the same.

UNITED STATES PATENT OFFICE

2,481,753

CLOTHESLINE REEL

Bertram E. Johnson, Newton, Iowa, assignor to Winpower Mfg. Company, Newton, Iowa, a corporation of Iowa

Application March 22, 1947, Serial No. 736,453

4 Claims. (Cl. 242—96)

1
The present invention relates to reels for clothes lines.

An object of the invention is the provision of such a reel by which the clothes line can be reeled up speedily.

Another object of the invention is the provision of a clothes line reel which is adaptable to simple and speedy manufacture, resulting in an economical article.

A further object of the invention is the provision of such a reel which will occupy very little space when stored.

Still another object of the invention is the provision of a simple reel which will hold a great length of clothes line.

The device is made entirely from wire stock, and needs no specially built parts for its construction.

With these and other objects in view, my invention consists in the construction, arrangement and combination of the various parts of my device whereby the objects contemplated are attained as hereinafter more fully set forth, pointed out in my claims and illustrated in the accompanying drawing, wherein:

Figure 1 is a side view of the device;

Figure 2 is an edge view of the device; and

Figure 3 is a line drawing of a modified form of device.

The preferred form of reel, as illustrated in Figures 1 and 2 comprises a central elongated shank 12 having its ends 14 bent out laterally from the main portion of the shank 12. The end portions 14 form handle members for operating the device.

The junctures between the handle members 14 and the shank 12 are in the form of loops 16 having their closed ends directed longitudinally outwardly of the shank 12. The loops 16 possess considerable lateral extent.

The material of which the shank 12 and handle members 14 are made is preferably ordinary wire stock. Such wire is easily formable in wire working machines, and possesses sufficient rigidity to retain its shape under ordinary conditions of use.

Secured to each end of the shank 12 is a pair of arms 18 which are also formed of wire stock. Each pair of arms 18 are formed from an integral piece of wire separate from the shank 12 and bent into the shape of a V, with the junctures 20 of the arms rounded similarly to the rounded portions of the closed ends of the loops 16. The extremities 22 of the arms 18 are bent

toward each other to parallel relation and extend longitudinally of the device.

The pairs of arms 18 are then secured to the shank 12 by fitting the rounded junctures 20 against the closed ends of the loops 16 and brazed thereto as indicated at 24. The lateral extent of the junctures 20 and loops 16 enable a considerable amount of braze material to be applied, resulting in a strong and rigid device.

10 The operator grips the handle portions 14 and, by turning the device with a cranking motion, can reel the clothes line over the ends of the device between the diverging legs 18. The inturned ends 22 of the legs 18 enable a considerable amount of line to be reeled thereon.

The device illustrated in Figure 3, is similar in general to the previous form, but instead of having handles 14 at the ends of the shank 12, it includes one handle 26 at one end of the shank, 20 and another, shown at 28, at substantially midway of the ends of the shank. The center piece is turned back forming a longer loop 30, which may be brazed at 32 to provide greater strength.

In using the device illustrated in Figure 3, the 25 length of the cranking stroke is reduced. Furthermore, wobbling is eliminated, since the handle 28 serves as an anchor or pivot point.

The device is very simple in construction, being 30 made entirely from ordinary wire stock. The device is flat and can be stored in a convenient place, occupying practically no space. The operations forming the individual pieces can be performed simply and economically; the shank 12 and handle members 14 form one piece, and each 35 pair of arms 18 form another piece. The next operation of brazing the pairs of arms 18 to the shank is also a simple operation.

While I have herein shown and described a preferred embodiment of my invention, manifestly it 40 is susceptible of modification and rearrangement of the parts without departing from the spirit and scope thereof. I do not, therefore, wish to be understood as limiting my invention to the precise form herein disclosed, except as I may be 45 so limited by the appended claims.

I claim as my invention:

1. In a device of the type described, an elongated shank, a handle member formed integral with said shank adjacent each end thereof, said handle members extending laterally from said shank on opposite sides thereof, and a pair of diverging arms formed separate from and secured to each end of said shank and extending longitudinally outwardly from the shank.

55 2. A reel of the class described, comprising, a

wire-like shank, the ends of said shank being bent laterally outwardly on opposite sides forming handle members, and a pair of wire-like diverging arms extending longitudinally outwardly from each end of said shank, said pairs of arms being secured to said shank at the bends between said shank and respective ones of said handle members.

3. A reel of the class described, comprising, a wire-like shank, the ends of said shank being bent laterally outwardly on opposite sides forming handle members, the junctures between said handle members and said shank being in the shape of loops having their closed ends directed longitudinally outwardly from said shank, and a pair of wire-like diverging arms extending longitudinally outwardly from each end of said shank, each pair of arms being formed of an integral piece, separate from said shank, the juncture between the arms of each pair being rounded, said pairs of arms being secured to said shank by joining the rounded junctures between the arms of the pairs to the closed ends of said loops.

4. A reel of the class described, comprising, a single-strand wire shank, the ends of said shank being bent laterally outwardly on opposite sides forming handle members, one of said handle members being positioned adjacent one end of

5 the shank, and the other handle member being spaced substantially midway between the ends of said shank, and a pair of wire-like diverging arms extending longitudinally outwardly from each end of said shank, said pairs of arms being secured to said shank at the bends between said shank and respective ones of said handle members.

BERTRAM E. JOHNSON.
